UNITED STATES PATENT OFFICE

THEODORE R. BETTENCOURT, OF NEW BEDFORD, MASSACHUSETTS, ASSIGNOR TO JOHN I. PAULDING, INC., OF NEW BEDFORD, MASSACHUSETTS, A CORPORATION OF MASSACHUSETTS

DESIGN FOR A LIGHTING FIXTURE

Application filed September 30, 1932. Serial No. 45,181. Term of patent 7 years.

To all whom it may concern:

Be it known that I, THEODORE R. BETTENCOURT, a citizen of the United States, residing at New Bedford, county of Bristol, Commonwealth of Massachusetts, have invented a new, original, and ornamental Design for Lighting Fixtures, of which the following is a specification, reference being had to the accompanying drawing, forming part thereof, in which the figure is a perspective view showing my new design.

I claim:

The ornamental design for a lighting fixture as shown.

THEODORE R. BETTENCOURT.
